UNITED STATES PATENT OFFICE.

FRED STEFFENS, OF ST. JOSEPH, MISSOURI, ASSIGNOR OF ONE-HALF TO HENRY L. DOHERTY, OF NEW YORK, N. Y.

ELEVATED-RAILWAY SYSTEM.

1,305,415.

Specification of Letters Patent. Patented June 3, 1919.

Application filed January 8, 1918. Serial No. 210,805.

To all whom it may concern:

Be it known that I, FRED STEFFENS, a citizen of the United States, residing at St. Joseph, in the county of Buchanan and State 5 of Missouri, have invented a certain new and useful Improvement in Elevated-Railway Systems, of which the following is a specification.

My invention relates to improvements in 10 elevated railway systems.

One of the objects of my invention is to provide an elevated railway system which will not interfere with street traffic, which will eliminate dangers and delays at rail- 15 road crossings, which may be cheaply constructed and economically operated, which is strong and durable, and which may be economically maintained in good condition.

A further object of my invention is to 20 provide an elevated railway system in which the cars in running will make little noise.

Still another object of my invention is to provide a novel track and truck wheels which will be self centering with respect 25 to the track, and which will eliminate lateral movement of the truck wheels on the track and the noisy friction which accompanies such movement.

Another object of my invention is to pro- 30 vide an elevated railway system which will permit of sharp curves being made by the cars with a minimum of friction.

A further object of my invention is to provide a novel track which will not have 35 its operation interfered with by weather conditions.

My invention further provides novel com- 40 pensating means by which the track and its support will readily adapt themselves to changes in temperature.

My invention further provides an elevated track and support therefor which will not materially darken the street or obstruct the street or sidewalks.

45 My invention provides further an elevated railway system in which each car or a train of cars may be operated by one man.

My invention provides further novel brak- 50 ing means which will eliminate the employment of brake shoes applied to the wheels of the trucks, and which will be substantially noiseless.

My invention further provides an ele- 55 vated railway system having suspended cars and a track support in which the tracks cross on the same level.

My invention provides further a novel housing for supporting the rails and protecting them from the elements.

My invention also provides a novel rail- 60 way crossing which permits trains to turn to the right or left, to run straight ahead or to turn around and return on another track.

My invention further provides a novel car 65 provided with novel means for suspending the car body from the trucks.

My invention also provides a novel rail- 70 way switch which is applicable to elevated or surface tracks.

My invention further provides further novel means for holding suspended cars from swaying laterally.

My invention provides further novel means for suspending elevated tracks which 75 permits of a maximum of strength and rigidity and a minimum of weight.

My invention provides still further cars having novel emergency exit means, by which the passengers may descend to the 80 street easily and safely when the cars are between stations.

Other novel features of my invention are hereinafter fully described and claimed.

In the accompanying drawings, which 85 illustrate the preferred embodiment of my invention,

Figure 1 is a side elevation of a portion of my improved elevated track and cars sup- 90 ported thereby.

Fig. 2 is a top view of that portion of the track shown in Fig. 1.

Fig. 3 is a cross section, enlarged, of that portion of the track shown in Fig. 1, two

cars being shown suspended respectively from the two tracks.

Fig. 4 is a side elevation, enlarged, of one of the cars and a portion of the track supporting the same.

Fig. 5 is a plan view of my improved elevated railway crossing.

Fig. 6 is a horizontal sectional view of my improved car and a portion of the guide therefor.

Fig. 7 is an enlarged cross section on the line 7—7 of Fig. 8, showing a portion of the track and a part of a car suspended therefrom.

Fig. 8 is a vertical sectional view on the line 8—8 of Fig. 7.

Fig. 9 is a top view, enlarged, of a spliced section of one of the rail supporting housings, partly broken away.

Fig. 10 is a side elevation, partly broken away, of what is shown in Fig. 9.

Figs. 11 and 12 are horizontal sectional views, taken on the line 11—11 of Fig. 10 and showing respectively the two rail joints of a track and supports therefor at the point of splicing of a housing.

Fig. 13 is a cross section of a portion of my improved car and the lateral guide therefor.

Fig. 14 is a horizontal sectional view, enlarged, of a portion of my improved crossing.

Fig. 15 is an enlarged vertical cross section on the line 15—15 of Fig. 6.

Fig. 16 is an enlarged vertical cross section of a portion of the car body and of the lateral guiding means for the same.

Fig. 17 is a horizontal sectional view of the guiding mechanism carried by the car and shown in Fig. 16.

Similar reference characters designate similar parts in the different views.

1 designates columns or pillars, preferably of structural steel, arranged in two rows at opposite sides of the street respectively, and at the edge of the sidewalks, in which position they will neither obstruct the street nor the sidewalks.

2 designates transverse spans supported by and respectively connecting oppositely disposed columns 1.

Mounted on the spans 2, which may be trusses of structural steel, are two pairs of longitudinal cables 3, Figs. 1 to 3, which are clamped between pairs of plates 4 which are mounted upon the spans 2.

Each pair of cables 3 supports at intervals pairs of clamping plates 5 and 6 disposed respectively above and below said cables, see Fig. 7.

Cross braces, or stiff legs 7, Figs. 2, 3 and 7, are secured to and respectively connect opposite pairs of clamping plates 5 and 6.

Extending vertically through and secured at their upper ends to each pair of clamping plates 5 and 6, are vertical bars 8, Figs. 3 and 7, which support at their lower ends a track comprising a longitudinal housing consisting of two longitudinal right-angled members 9, Fig. 7, which are embraced by and are secured to and supported by a plurality of vertical brackets 10, to which the lower ends of the bars 8 are pivoted by longitudinal horizontal bolts 11.

The brackets 10 are, preferably, of inverted U-shape, the lower ends of the arms thereof having inward extensions 12, which support inwardly extending longitudinal flanges 13 with which the members 9 are respectively provided.

Mounted respectively on the flanges 13, within the housing, and bolted thereto, are two rails 14, Fig. 7, which are respectively at opposite sides of a longitudinal bottom opening with which the housing is provided.

The upper side of each rail 14 is arcuate preferably concave so as to render the truck wheels self centering and to reduce noise and friction as will be described hereinafter.

Cross braces or stiff legs 15, Figs. 3 and 7, similar to the cross braces 7, are secured to and respectively connect opposite brackets 10 of the two tracks carried by the two pairs of cables 3.

Secured to and supported by the arms respectively of the brackets 10 of each track are two longitudinal inverted troughs 16 which cover and protect two trolley wires 17, Fig. 7, which are secured to and supported respectively by the troughs 16.

Supported by the cross braces 15 is a longitudinal guide, Fig. 3, and Fig. 16, designed to hold the suspended cars which run on the two tracks from lateral swaying when rounding curves or during the presence of high cross winds. Preferably this longitudinal guide consists of a longitudinal framework comprising vertical bars 18, arranged in pairs with their upper ends secured to and suspended from the cross braces 15 and having their lower ends secured to and supporting transverse bars 20 to the under sides of which are secured brackets 21, Fig. 16, which are bolted to and embrace longitudinal guide bars 19, which are concave on their under sides and are adapted to have run therein peripherally curved tires 22 provided on guiding rollers 23, rotatably mounted on the transverse arm 24 extending inwardly from a vertically movable vertical plate 25, Figs. 16 and 17, having rotatably mounted thereon an upper pair of rollers 26 and a lower pair of rollers 27, which run in and are guided by a vertical tubular guide plate 28 secured to the adjacent vertical side of the car body 29.

The inner vertical side of the tubular guide 28 is provided with a longitudinal slot 30, through which the arm 24 extends.

For normally forcing the wheel 23 upwardly into engagement with the guide bar 19, I provide yielding means comprising, preferably, a weight 31, Figs. 16 and 17, which has attached to its upper end one end of a chain 32, the other end of which is attached to the arm 24. The chain 32 is supported by and runs over two pulleys 33 and 34, supported rotatably on a bracket 35 which is secured to the car body 29 and extends through the vertical wall thereof above the guide plate 28. The pulleys 33 and 34 are located respectively in the interior and at the exterior of the car body. The weight 31 may be slidably mounted in a tubular guide 36 secured to the inner side wall of the car body. As shown in Fig. 3, crossed diagonal braces 37, each provided with a turn buckle 38 may connect opposite bars 18. As shown in Fig. 1, diagonal braces 39, each having a turn buckle 40 may have their lower ends secured to the lower ends of the bars 18 and their upper ends secured to the upper ends of some of the bars 18.

Crossed horizontal diagonal braces 41, each having a turn buckle 42, Fig. 2, have their ends secured to the brackets 10 of opposite tracks. Inclined longitudinal braces 41', each having a turn buckle 42', Fig. 1, may have their upper ends respectively secured to adjacent clamping plates 5, and their lower ends respectively secured to adjacent tracks 10.

I will not describe the trucks and the means of suspending therefrom the car body. Referring particularly to Fig. 4 and also to Figs. 3, 7 and 8, it will be noted that each car body 29 is suspended on vertical axes from two trucks. Each truck comprises the following described parts. In the concave upper sides of two rails 14, Fig. 7, are two pairs of wheels 43, having rubber tires 44 fitting in the curved upper sides of the rails 14. The wheels 43 are splined respectively to two cross shafts 45, rotatable in the head of a T-shaped support comprising two plates 46 and 47 bolted together and extending downwardly through a bottom opening provided between the flanges 13 of the housing members 9.

The lower ends of the plates 46 and 47 are respectively secured to the upper sides of two semi-circular cup-shaped plates 48 and 49, which are provided at their lower edges respectively with inwardly extending flanges 50 and 51, which support a horizontal annular plate 52, which has a ball race in its upper side in which are located balls 53 which are mounted in a ball race in the under side of a horizontal annular plate 54,

which supports a circular plate 55, as is best shown in Figs. 7 and 8.

Extending vertically through the car body 29 and through the plate 55 are vertical bars 56, Figs. 7 and 8, which at their lower ends are provided with nuts 57 which respectively support coil springs 58, Fig. 4, which in turn bear against and support the under side of the car body 29.

Respectively encircling the upper ends of the bars 56 are coil springs 59, Figs. 7 and 8, which are supported by the upper side of the plate 55, and which have respectively mounted upon their upper ends washers 60, which support nuts 61 with which the upper ends of the bars 56 are respectively provided.

The bars 56, springs 58 and 59, washers 60 and nuts 57 and 61 provide yielding means for suspending the car body 29 from each of the two trucks. The two plates 55 being respectively rotatably mounted, on vertical axes, with respect to the flanges 50 and 51, permit the cars, although they may have long bodies, to make sharp turns, as the wheel base of each truck may be short.

As the car body moves vertically, as permitted by its supporting springs, the weight 31 holds the wheel 23 in operative action with the guide bar 19 with which it engages. The car body is thus held from swaying laterally.

Mounted respectively on the members 46 and 47, Figs. 7 and 8, are two tubular standards 62, in each of which is mounted a vertical coil spring 63, Fig. 8, which supports the lower end of a plunger 64, upon the upper end of which is rotatably mounted a trolley wheel 65, which engages with the adjacent trolley wire 17, against which it is held by the spring 63.

Two levers 66 are respectively pivoted to the plates 46 and 47, and respectively engage two washers 67 secured respectively to the plungers 64 at the upper sides thereof. To each lever 66 is secured a rope 68 which permits the operator of the car to draw the trolley wheel 65 adjacent thereto downwardly out of contact with the trolley wire engaged by it. One trolley wire 17 may serve for a supply wire and the other for the return of the current.

For bracing the trucks, each truck is provided with two chains 69, Fig. 8, secured at their lower ends to the plate 49 and at their upper ends to the head of the T-shaped plate 47 at opposite sides respectively of the stem thereof.

For propelling the car, each truck is provided with the following described mechanism.

Rotatably mounted in suitable bearings provided in the plates 46 and 47 is a horizontal transverse shaft 70, to which, between

the plates 46 and 47, is rigidly secured a chain wheel 71, which is connected by a driving chain 72, preferably of the noiseless type, Figs. 4, 7 and 8, which passes over and 5 operatively engages two chain wheels 73 respectively secured, between the plates 46 and 47, to the two shafts 45.

For driving each shaft 70, there are preferably provided two electric motors 74, 10 mounted respectively on the horizontal lower ends of the plates 46 and 47.

Rigidly secured to the shaft 70 are two 15 brake wheels 75, which are respectively bolted to two disks 76, Fig. 7, which are respectively rigidly secured to the two armature shafts 77 of the motors 74. Driving connection is thus established between the armature shafts 77 and the shafts 45, to which the truck wheels 43 are secured.

20 For protecting the rollers and lower parts of the truck mechanism, a casing 78 secured to the plates 46, 47, 48 and 49, and inclosing the motors 74, as shown in Figs. 3 and 7, may be provided, the motors being secured, 25 as shown, to the inner walls thereof.

Between each pair of wheels 43 of each truck is provided a track brake shoe 79, Fig. 8, which has a curved under side fitted to the upper curved side of the adjacent rail 14, 30 against which the brake shoe is adapted to be forced by a vertical piston 80, which is attached to the brake shoe and which is slidably fitted in the usual manner in an air cylinder 81, to which is connected, above the 35 piston 80, a train pipe 82, which is connected to a suitable compressed air tank, not shown, carried by the car.

An emergency brake mechanism is also provided, see Fig. 7, on each truck. This 40 brake mechanism comprises the brake wheels 75, which are provided with peripheral grooves, curved in cross section, in which are fitted and adapted to bear at the under sides thereof two brake shoes 83, which 45 are respectively pivotally mounted upon two levers 84 and 85, which are respectively pivoted on horizontal axes to two brackets 86 and 87, which are respectively mounted upon the lower horizontal portions of the plates 50 46 and 47. The inner ends of the levers 84 and 85 are respectively pivoted to the lower ends of the outer arms of two inverted U-shaped piston rods 88, the inner arms of which are respectfully secured to two piston heads 55 89, which are respectively reciprocatively fitted in two upright air cylinders 90, which are respectively secured to the outer sides of the plates 46 and 47.

Two air pipes 91, respectively communicate with the cylinders 90 below the piston heads 89. The air pipes 91 are connected with the air pressure tank before referred to. When compressed air is admitted to the cylinders 90, through the pipes 91, the

brake shoes 83 will be forced upwardly 65 against the brake wheel 75 through the intermediary of the piston heads 89, the piston rods 88, and the levers 84 and 85.

In order that the brake shoe 83, which is carried by the lever 84, may be applied by 70 hand, the lever 84 has attached to it a rope 92 which extends downwardly into the car body, see Fig. 7. By pulling down on the cable or rope 92, the lever 84 is swung so as to throw the brake shoe 83 carried by it 75 against the under side of the adjacent brake wheel 75.

To allow for changes in temperature, each track housing is provided, preferably at each cross span 2, with an expansion joint, see 80 Figs. 9 to 11, in which longitudinal sections comprising the members 9, are slidably mounted in and overlapped by an intermediate section consisting of plates 93 in which are mounted transverse bolts 94, which extend through and are slidably respectively in longitudinal slots 95 provided in the members 9.

Vertical bolts 96 mounted in the adjacent span 2 extend through longitudinal slots 97 90 provided in the members 9.

At the expansion joints, the rails 14 overlap the spaces between the ends of adjacent members 9 to which the rails are secured by vertical bolts 98 which extend through 95 longitudinal slots 99 provided in the flanges 13 of the members 9. As shown in Figs. 11 and 12, the rails 14 have oblique overlapping side edges 100, whereby jolting of the truck wheels in passing from one rail to the next 100 will be avoided.

In order that two of the tracks may cross another pair at the same level, I provide the crossing mechanism illustrated in Fig. 5.

At such a crossing there are four columns 105 or pillars 1 which are connected by spans 2 to form a square. The pillars 1 are connected by crossed diagonal spans 101 corresponding in structure to the spans 2. The spans 101 support a platform 102, disposed centrally and supporting switch levers 103 to which are respectively connected rods 104 which are respectively pivoted to switch tongues 105, Fig. 14, which will be described later.

Located centrally between the four columns 1 is an arcuate track 106, preferably a complete circle, and similar in construction to the straight track having the housing members 9 already described. Each crossing 120 track comprises two straight sections A, Fig. 5, and two curved portions B, the latter merging with the circular track 106 and forming continuations of the adjacent curved portions B of the adjacent track. 125 This may best be seen in Fig. 14, in which it will be observed that at each juncture of the curved portions B with the circular track 106,

there are two switch tongues 105, which are pivoted respectively to the places of intersections of the outer rails 14 of the circular track 106 with the adjacent rails 14 of the 5 curved portions B of the crossing tracks, the tongues 105 being respectively pivoted by vertical bolts 107 to the rails 14.

Thus at each switch, there are two tracks which merge into a single track across which 10 each tongue 105 is adapted to swing so as to operatively engage either rail 14, each of the latter at the point where there is a single track being provided in its upper side and inner edge with a notch 108, Fig. 14, which 15 is adapted to receive the free end of the adjacent tongue 105.

By means of the structure just described, the wheels 43 will be supported in passing from the curved portions B onto the circular track. At the same time, the truck plates 20 46 and 47 are enabled to pass from either curved portion B onto the circular track and from that track to the other tracks.

With the crossing structure just described, 25 any train on any track may continue straight ahead, turn to the right or left, or turn around and return on the track which is parallel to the one on which it has been running.

In case that a car, for some reason is 30 stopped between stations, and it is desired to unload the passengers, I provide each car with an emergency ladder 109, see Figs. 1, 3, 4, 6 and 15, which is hinged at one end to the under side of the bottom of the car adjacent to an opening in the floor, which is 35 normally covered by a trap door 110, Fig. 6. The ladder may be raised and lowered by means of a cable 111, which is fastened to and adapted to be wound on a drum 112, 40 Fig. 15, which is rotatably mounted under a seat in the car and which is provided with a crank 113, to which is secured a ratchet wheel 114, with which engages a pawl 115 normally held by a spring 116 in engagement 45 with the ratchet wheel. By releasing the pawl 115, the drum 112 may be controlled by the crank 113 so as to lower the free end of the ladder to the street, or the crank may be turned so as to raise the ladder to the 50 horizontal position shown in the drawings.

117 designates elevated platforms which are reached by stairs 118, by means of which passengers may get on or alight from the cars at the stations.

55 Each car is provided in one side near the forward end thereof with entrance doors 119 and exit doors 120.

Between the entrance and exit doors, Fig. 6, is a transverse railing 121. Spaced apart 60 from the inner end of the railing is a longitudinal table 122 behind which is the conductor's station from which he can control a turn stile 123 which controls the passage of passengers, between the table 122 and the

railing 121, from the forward to the rear 65 part of the car.

All passengers leaving the car at the exit 120 will have passed the turnstile and their fares will have been collected.

In order that the conductor, who is also 70 the motorman of the car, may observe the track ahead, the car body is provided with a front window 124, located just forward of the conductor's station at the rear end of a longitudinal passageway 125, Figs. 6 and 75 13, with which the forward end and one side of the car is provided. The location of the conductor's station is such that he can have full observation of all the passengers in the car and those entering and leaving, 80 as well as of the truck ahead and of the stations at which the car stops.

By means of the structure described, a 85 relatively light and very strong, economical and durable track support is provided. Owing to the manner of suspending the cars, the cars can be relatively light and yet be suitable for heavy traffic, which may be carried on without any interference with the street or sidewalk traffic. The elevated 90 structure is well adapted for level or hilly places and can be very cheaply built and maintained.

I do not limit my invention to the structures described and shown, as modifications, 95 within the scope of the appended claims, may be made without departing from the spirit of my invention.

What I claim is:—

1. In an elevated railway system, an elevated track, a truck running on said track, a car body yieldingly suspended from said truck, a longitudinal guide, and means including a vertically movable guiding device carried by the car body and engaging 105 said guide for holding the car body from lateral swinging.

2. In an elevated railway system, an elevated track, a truck running on said track, a car body yieldingly suspended from said truck, a longitudinal guide, a vertically movable guiding device carried by the car body and engaging said guide for holding the car body from lateral swinging, and yielding means for normally holding said 110 guiding device in operative engagement with said guide.

3. In an elevated railway system, two tracks, means for suspending said track independently of each other, cross-braces connecting said track suspending means, and car guiding means suspended from said 115 cross braces.

4. In an elevated railway system, two tracks, two longitudinal closed housings in 125 which said tracks are respectively contained and supported, means for suspending said housings, cross braces connecting said hous-

ings, and car guiding means suspended from said cross braces.

5. In an elevated railway system, two tracks, two longitudinal closed housings in which said tracks are respectively supported, means for supporting said housings, cross braces connecting said housings, and a longitudinal guide carried by said cross braces for holding the cars running on said

10 tracks from lateral swinging.

6. In an elevated railway system, track suspending means, a track carried thereby, a longitudinal frame carried by said suspending means, an inverted longitudinal trough

guide carried by said frame, a truck running 15 on said track, a car body suspended from the truck and guiding means carried by said car body and running in said guide.

7. In an elevated railway system, a truck, a car body suspended therefrom, an inverted 20 longitudinal trough guide, a vertically movable guiding device carried by the car body and adapted to run in and be guided by said guide, and means for normally forcing said device upwardly into said guide. 25

In testimony whereof I have signed my name to this specification.

FRED STEFFENS.
